FOOT PROTECTOR

George A. Moriarty, San Diego, Calif.

Application July 16, 1937, Serial No. 153,963

18 Claims. (Cl. 36—72)

This invention relates to foot protectors and represents improvements on my prior Patent No. 2,017,690.

It is an object of the invention to provide a foot protector for protecting the foot from injury, especially from heavy objects falling upon the toes or instep portion.

Particularly it is an object of the present invention to provide a foot protector of the above character which may be easily and quickly applied to a shoe.

Another object of the invention is to provide a foot protector which, while serving to effectively protect both the toe and instep portions of the foot from being injured by falling objects, will not cause discomfort to the wearer while walking.

A further object of the present invention is to provide a foot protector which may be readily adjusted to fit divers sizes of shoes and which when so adjusted may be effectively maintained in position on the shoe.

In attaining these objects there is provided, as a feature of the invention, a foot protector which is adapted to rest upon the welt of a shoe and which is maintained in position on the shoe by means of a resilient connection between the foot protector and means engaging the instep portion of the shoe sole.

Another feature of the invention resides in the provision of a pair of interfitting shells shaped to overlie the shoe upper, having means adapted to rest upon the welt of the shoe and with which there is associated novel locking means by which the shells may be locked relatively to each other in divers wide and close-spaced positions.

A further feature of the invention resides in providing a foot protector which includes not only a shaped shell adapted to overlie the toe portion of the shoe but which also includes a second shell shaped to overlie the instep portion of the shoe. A complementary feature is the provision of a pivotal connection between the toe and instep shells whereby there is no interference with the regular flexing of a person's foot.

A further feature of the invention resides in providing a shaped shell adapted to rest upon the welt of a shoe, which is advantageously held in position by means of resilient connections to a novel wedging means cooperable with the shank portion of the shoe sole. A complementary feature is the provision of a foot protector including a pivotally connected toe portion and instep portion with a single yielding means adapted to hold both portions on a shoe.

A further feature of the invention resides in

providing a foot protector which includes a pair of interfitting shells movable laterally toward and away from each other, with which is provided novel means for guiding the shells during their lateral movement.

Another feature of the invention resides in providing a foot protector of the above character which is sturdy in construction, which is not cumbersome and which may be readily associated with a shoe.

Other objects and features of the invention will hereinafter appear.

In the drawings:

Figure 1 is a top view of one form of the present invention.

Fig. 2 is a side view of the foot protector shown in Fig. 1.

Fig. 3 is a rear view partially in section, taken on the line 3—3 of Fig. 2.

Fig. 3A is a fragmentary detail view showing a modified form of abutment.

Fig. 4 is a bottom view of the foot protector shown in Fig. 1.

Fig. 5 is a top view of a modified form of the invention.

Fig. 6 is a fragmentary top view of another modified form of the invention.

Fig. 7 is a rear view of another modified form of the invention.

Fig. 8 is a top view similar to Fig. 1 of the form of the invention shown in Fig. 7.

Fig. 9 is a side view of the foot protector shown in Figs. 7 and 8.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Referring now more particularly to the drawings for the present preferred embodiments of the invention and first to Figs. 1 through 4 there is disclosed a foot protector 20 comprising a main shell 21, of metal or other rigid material, shaped to provide a chamber 22 to envelope the toe portion 23 of a shoe 24 shown in dotted lines. This main shell, as shown, is formed by a pair of interfitting shells 25 and 26 having a telescoping connection 27 at the top. Preferably the telescoping connection comprises a flat section 28 on the shell 25 and a plate 29 which, as shown, may be

advantageously connected to the shell 26 by rivets to form with a flat offset top section 30 thereof a socket 31 adapted to snugly and slidably receive the flat section 28.

5 With the telescoping connection provided by the present invention it is possible to move the shells 25 and 26 laterally relative to each other to divers wide and close-spaced positions, and thus adapt the main protecting shell 21 to fit 10 shoes of different widths.

Now of particular importance it is to be noted that there is provided in the offset section 30 an aligned series 32 of holes 33, 34, 35, 36 and 37, in the plate 29 a series 32' of holes 33', 34', 35', 15 36' and 37' in alignment and registering respectively with the holes in series 30, and in the flat section 28 of the shell 25 a series 38 of holes 39, 40, 41, 42 and 43 deposited at an angle to the aligned series 32 and 32' in the shell 26. As 20 shown, a U-shaped spring 44 is secured to the underside of the plate 26 and is positioned so that the spring arms 45 thereof extend contiguous the series 32' of holes therein so that when a locking pin 46 is, for example, inserted in the mating 25 holes 35 and 35' in the shell 26 and the hole 41 in the shell 25 the spring arms 45 snap into the pin groove 47 to hold the pin in position. In this manner the interfitting shells 25 and 26 are locked from movement laterally relative to each 30 other.

With this construction, also, it will be readily appreciated that when it is desired to adjust the shells 25 and 26 to accommodate shoes of different widths it is merely necessary to withdraw 35 the locking pin 46, move the shells laterally relative to each other to bring the desired other holes in register and then insert the pin 46 in the registering holes.

Thus, assume that it is necessary to adjust the 40 shells to a wider spaced position than shown. In such a case the shells 25 and 26 may be moved relative to each other until the hole 37 in the offset section of the shell 26 is in register with the hole 43 in the flat section of the shell 25 and the locking pin 46 then inserted. Similarly, if it 45 is necessary to adjust the shells to a more close-spaced position, they may be moved until the hole 33 in the offset section of the shell 26 is in register with the hole 39 in the flat section of the shell 25. It will be appreciated that the interfitting shells may be locked in intermediate wide 50 and close-spaced positions by moving the same so as to bring into register other of the holes.

For maintaining the shells 25 and 26 in proper 55 position relative to each other longitudinally and for guiding them during their lateral movement there is carried between the offset section 30 and plate 29 in the socket 31 a pair of spaced guide pins 48 and 49 entering laterally extending slots 60 50 and 51 in the flat section 28 of the shell 25.

If desired, however, instead of utilizing a pin and slot means to maintain the shells in proper position longitudinally relative to each other, there may be utilized the cooperating rib construction 65 shown in Fig. 5. As there illustrated, a pair of transversely extending ribs 52 and 53 are formed on the shell 26 to respectively cooperate with ribs 54 and 55 in alignment therewith on the shell 25. Thus, adverse relative longitudinal movement of the shells is prevented by the engagement of the ribs. These ribs also serve to strengthen the shells, and thereby make possible the attainment of considerable strength even though light gauge metal is used. In all 70 other particulars the construction shown in Fig. 75

5 is identical with the form illustrated in Figs. 1 through 4.

To provide a support for the main shell 21 abutments 56 and 57 are formed on the bottom edges of the interfitting shells 25 and 26 respectively. Preferably, and as shown, these abutments are provided by flanges 58 and 59 extending inwardly at the lower edges of the shells 25 and 26 and adapted to rest upon the welt 60 of a shoe. In addition to serving as supporting 10 means the flanges may also serve as a gripping means to engage between the welt and the shoe upper. However, as shown, spaced lugs 61 may advantageously be formed to extend inwardly from the flanges 58 and 59 to grip the shoe and 15 to provide additional means for supporting the protector 20 on the shoe.

While the flange type abutment is preferred, a modified abutment 62 may be provided by curving slightly inwardly the lower side walls 20 of the shells as shown in Fig. 3A. This modified form of abutment is more fully described in my prior Patent No. 2,017,670.

Whether the abutment utilized is of the preferred form or the modified form shown in Fig. 25 3A, it is thus seen that when the interfitting shells are adjusted laterally to the proper position and locked by means of the pin 46 that the protector 20 is effectively supported on the welt 60 so that should any objects be dropped upon 30 the shoe the foot of the wearer would be fully protected from being crushed or otherwise injured due to an inadvertent slipping of the protector from the welt.

For insuring the maintenance of the protector 35 in position on the shoe there is provided a novel yoke member 63 adapted to be inserted under the shank or instep portion 64 of the sole 65, having upstanding side flanges 66 and 67 with hooked portions 68 and 69 respectively extending 40 over the welt at opposite sides of the shoe.

Preferably this yoke member 63 is of a width in excess of that of the narrowest part of the shank portion 64 to enable its being easily inserted in position, but is narrower than the 45 forward ball portion 70 of the sole and forward portion of the shank so that when pulled forwardly it will wedge against the rear sides of the latter portion. An effective means for thus pulling the yoke member forwardly is provided by 50 spring connectors 71, each comprising a coil spring 72 having a button 73 secured to the forward end adapted to be inserted in a suitable button opening 74 and pulled into an associated rearwardly extending slot 75 in each of the side 55 walls of the shells 25 and 26, and having a plate section 76 secured at the other end with a loose rivet connection to the respective upstanding side flanges 66 and 67 of the yoke member.

With this advantageous construction the yoke 60 member is urged into wedging engagement with the sole and the protector is held firmly in position on the shoe with the abutments resting upon the welt and drawn inwardly to grip the sides of the shoe upper. It is to be particularly noted that 65 a foot protector constructed in the manner above described may be most easily adjusted to fit shoes of different sizes and that when associated with the shoe may be easily and securely maintained in position by merely inserting or snapping the 70 yoke member under the shank portion of the sole.

If desired, in order to protect the instep portion as well as the toe portion of the foot from 75 injury from falling objects the interfitting shells

25 and 26 comprising the main shell 21 may be extended rearwardly. Preferably, however, when it is desired to provide a shield for the instep portion of the foot there is provided a second main shell 77, of metal or other rigid material, shaped to provide a chamber 78 to envelope the instep portion of the shoe as shown in Figs. 7 through 9. This instep protecting shell 77, as in the case of the toe protecting shell 21, is formed by a pair of interfitting shells 79 and 80 having a telescoping connection 81 at the top. As also in the case of the interfitting shells 25 and 26 the telescoping connection comprises a flat section 82 on the shell 79 and a plate 83 which, as shown, 10 may be advantageously connected to the shell 80 by rivets to form with the flat offset top section 84 thereof a socket 85 adapted to snugly and slidably receive the flat section 82.

For enabling a locking of the interfitting shells 20 79 and 80 relative to each other in divers positions of lateral adjustment there are provided, as with the interfitting shells 25 and 26 enveloping the toe portion, a series 86 of holes 87, 88, 89, 90 and 91 in offset section 84, a series 86' of holes 87', 25 88', 89', 90' and 91' in the plate 83 of shell 80 in register with the respective holes in the series 86, and another series 92 of holes 93, 94, 95, 96 and 97 in the flat section of the other shell 79 disposed at an angle to the registering series 86 and 30 86' in the shell 80.

Also, a locking pin 98 with a locking groove 99 is provided, adapted to be inserted in position when the interfitting shells 79 and 80 are moved laterally relative to each other to bring a selected 35 mating hole in the series 92 in register with mating holes in the series 86 and 86'. A U-shaped locking spring 100 may be advantageously secured to the underside of the plate 83 so as to position the spring arms 101 thereof contiguous the series 40 86' of holes to snap into the groove 99 of the locking pin.

Likewise, as with the interfitting shells 25 and 26, there is provided for maintaining the shells 79 and 80 in proper position relative to each other longitudinally, and for guiding them during their lateral movement toward and away from each other, a pair of spaced guide pins 102 and 103 carried between the offset section 84 and plate 83 in the socket 85 and movable respectively in transversely extending slots 104 and 105 in the flat section of the shell 79.

To support the instep protecting shells 79 and 80 there are formed thereon abutting flanges 106 and 107 respectively, which extend inwardly to 55 rest upon the welt of a shoe similarly to the abutments 56 and 57 on the toe protecting interfitting shells 25 and 26.

In addition, there are also provided on the shells 79 and 80 downwardly extending abutting lugs 60 108 and 109 respectively adapted to engage with the floor or other walking surface to further support the shells when a heavy object is dropped thereon. Preferably, these lugs 108 and 109 are of such a length that they are normally maintained slightly clear of the walking surface by the flanges 106 and 107 resting on the shoe welt, but are close enough to the walking surface to quickly engage the latter when a heavy object strikes the protecting shells. This construction 65 is advantageous in that it offers a supplementary support that when necessary will positively engage the walking surface, but which normally will be maintained clear thereof so as not to interfere with the walking of the workman or other person wearing the protector. Preferably the

set of flanges 106 and 107 as well as the set of lugs 108 and 109 are used. However, either set of these lugs may be used alone.

In order that the instep protecting interfitting shells 79 and 80 may be maintained in proper relation with the toe protecting interfitting shells 25 and 26 there are provided on the shells 79 and 80 pivot fingers 110 and 111 adapted to be inserted in the button openings 74 at the head of the button slots 75 in the shells 25 and 26. With 10 this construction it is seen that a pivotal connection is provided between the toe and instep protectors 20 and 112 so that the latter protector may move upwardly and downwardly as the shoe sole is flexed during walking.

Also, it is to be particularly noted that when thus pivotally associated the forward portions of the instep protecting shells 79 and 80 are spaced above and slightly overlie the rear portions of the toe protecting shells 25 and 26 so as to provide 20 complete protection for the forward portion of the foot.

It is further seen that the inwardly extending abutting flanges 106 and 107 on the shells 79 and 80 are of such a width as to maintain the 25 side walls of the latter sufficiently clear of the shoe upper to permit the spring connectors 71 to pass on the inside thereof.

To associate the two-part protector shown in Figs. 6 through 8 with a shoe the same general 30 operations are entailed as when associating the single protector 20. In addition, it is merely necessary to properly adjust the shells 79 and 80 of the instep protector to the proper spaced relation to be supported on the shoe welt and 35 to grip the shoe upper in the same manner as the shells 25 and 26 of the toe projecting part 20. The spring connectors 71 serve effectively maintain both protectors 20 and 112 in position on the shoe. The connectors 71 entering channels 71' may also serve to locate and maintain 40 the second shell 77 relative to the shoe.

If desired, and as shown in Fig. 6, a pivot connection 113 may be provided between the interfitting shells 25 and 26 of the toe protector 20 45 at the forward end thereof. With such a construction it is possible to dispense with the locking pin 46 as the pull of the spring connectors will serve to maintain the abutments 56 and 57 on the shoe welt and the gripping lugs or flanges 60 61 in engagement with the sides of the shoe upper.

Variations and modifications may be made within the scope of this invention and portions of the improvements may be used without others.

Having thus described the invention, what is claimed as new is:

1. A foot protector comprising a shaped metal shell; an abutment on said shell adapted to rest upon the welt of a shoe; a yoke member adapted to be inserted under the instep section of the shoe sole; hooks on said yoke member adapted to overlie the welt; and resilient means connecting said yoke member and said shell for urging the latter member forwardly into wedging engagement with the sole and maintaining the shell in position on a shoe.

2. In a foot protector the combination of a shell of rigid material, shaped to envelope the toe portion of a shoe; an abutment on said shell adapted to rest upon the welt of a shoe; a second shell of rigid material, shaped to envelope the instep portion of a shoe; abutment means on said second shell adapted to rest upon the welt of a shoe; a pivotal connection between said first 75

and second shells and independent of the shoe; and means for maintaining said shells in position on a shoe.

3. In a foot protector the combination of a shell connectable to and shaped to envelope the toe section of a shoe; an abutment on said shell adapted to rest upon the welt of a shoe; a second shell, shaped to envelope the instep portion of a shoe; a pivotal connection between said

10 first and second shells and independent of the shoe; and means for maintaining said shells on a shoe.

4. In a foot protector the combination of a pair of interfitting and adjustable members defining together a shaped shell of rigid material; abutment means on said shell adapted to rest upon the welt of a shoe; means for maintaining said interfitting members in divers positions of adjustment to vary the width of said shell; 20 clamping means for engagement with opposite sides of a shoe sole rearwardly of said shell; and resilient means connecting said clamping means and said shell to maintain the latter in position on a shoe.

25 5. In a foot protector the combination of a pair of shells; a telescoping connection between said shells, permitting spreading thereof; means for maintaining said shells in divers spread positions relative to each other; abutment means 30 on said shells adapted to rest upon the welt of a shoe; yoke means insertable under the shank portion of the sole of a shoe, having hook portions adapted to overlie the welt of a shoe; and resilient means connecting said yoke means and 35 said shells to maintain the latter in position on a shoe.

6. In a foot protector the combination of a pair of interfitting shells, one of said shells having a series of holes and the other of said shells 40 having another series of holes disposed at an angle to said first series; a locking pin insertable in selected holes in said two series for locking said shells together in divers spread positions relative to each other; means on said shells for 45 supporting the latter on the welt of a shoe; and means for maintaining said shells in position on a shoe.

7. In a foot protector the combination of a pair of interfitting shells, one of said shells having a series of holes and the other of said shells 50 having another series of holes disposed at an angle to said first series; a locking spring disposed contiguous one of said series of holes; a locking pin having a spring receiving groove, insertable in selected holes in said two series for locking said shells together in divers spread positions relative to each other; means on said shells for supporting the latter on the welt of a shoe; and means for maintaining said shells in 55 position on a shoe.

60 8. In a foot protector the combination of a pair of shells; a telescoping connection between said shells for permitting movement thereof laterally toward and away from each other; a pair of pin 65 and slot means spaced longitudinally of the shells for guiding said shells during said lateral movement; means for locking said shells relative to each other in divers lateral positions; abutment means on said shells adapted to rest upon the 70 welt of a shoe; yoke means insertable under the instep portion of the shoe sole for engagement with opposite sides thereof; and resilient means connecting said yoke means and said shells to maintain the latter in position on a shoe.

75 9. In a foot protector the combination of a

pair of interfitting shells, movable laterally toward and away from each other; means on said shells adapted to rest upon the welt and to grip the upper of a shoe; means for locking said shells relative to each other in divers lateral positions; clamping means engageable with the sides of the sole of a shoe; and spring means connecting said clamping means and said pair of shells to maintain the latter in position on a shoe.

10. In a foot protector the combination of a pair of interfitting shells movable laterally toward and away from each other; aligned and co-operating ribs on said pair of shells, extending transversely thereof to provide a guide means for said shells during said lateral movement; means for locking said shells relative to each other in divers lateral positions; abutment means for resting upon the welt of a shoe upper; resilient means extending rearwardly from said shells for maintaining the latter in position on a shoe and 20 clamping means engageable with opposite sides of the shoe sole and connected to said resilient means for securing the latter to the shoe.

11. In a foot protector the combination of a shell of rigid material, shaped to envelope the toe portion of a shoe; an abutment on said shell adapted to rest upon the welt of a shoe; a second shell of rigid material, shaped to envelope the instep portion of a shoe; means on said second shell adapted to rest upon the welt of a shoe; means on said second shell positioned to extend beside the welt of a shoe and to engage the walking surface; a pivotal connection between said first and second shells and independent of the shoe; and means for maintaining said shells in position on a shoe.

12. In a foot protector the combination of a pair of interfitting shells; a pivotal connection between said shells; means on said shells adapted to rest upon the welt of a shoe; clamping means engageable with the shank portion of the sole of a shoe at opposite sides thereof; and resilient means connecting said engaging means and said shells to maintain the latter in position on a shoe.

13. In a foot protector the combination of a pair of interfitting members defining together a shell adapted to envelope the toe portion of a shoe and movable laterally toward and away from each other; means on said members adapted to rest upon the welt of a shoe sole; means for locking 5 said members relative to each other in divers lateral positions; a second pair of interfitting members movable laterally toward and away from each other, defining a shell adapted to envelope the instep portion of a shoe and to overlap a portion of said first named shell; means for locking 5 said last named members in divers lateral positions; pivotal connections between said members in said first and second named shells; and means for maintaining said shells in position on a shoe.

14. In a foot protector the combination of a pair of interfitting shells adapted to envelope the toe portion of a shoe and movable laterally toward and away from each other; means on said shells 6 adapted to rest upon the welt of a shoe; means for locking said pair of shells relative to each other in divers lateral positions; a second pair of interfitting shells adapted to envelope the instep portion of a shoe and movable laterally toward 7 and away from each other; means for locking said second pair of shells relative to each other in divers lateral positions; means on said second named shells adapted to engage the walking surface; pivotal connections between said first and 7

second named pair of shells; yoke means insertable under the shank portion of the sole of a shoe and having hook portions adapted to overlie the welt of a shoe; and resilient means connecting said yoke means and said first named pair of shells for maintaining the latter and said second named pair of shells on a shoe.

15. In a foot protector the combination of a pair of interfitting shells adapted to envelope the toe portion of a shoe and movable laterally toward and away from each other; means on said shells adapted to rest upon the welt of a shoe; means for locking said pair of shells relative to each other in divers lateral positions; a second 15 pair of interfitting shells adapted to envelope the instep portion of a shoe and movable laterally toward and away from each other; means for locking said second pair of shells relative to each other in divers lateral positions; means on said second named shells adapted to rest upon the welt of a shoe; pivotal connections between said first and second named pairs of shells; and means for maintaining said pair of shells on a shoe.

16. In a foot protector the combination of a 25 pair of interfitting shells adapted to envelope the toe portion of a shoe and movable laterally toward and away from each other; means on said shells adapted to rest upon the welt of a shoe; means for locking said pair of shells relative to each other in divers lateral positions; a second 30 pair of interfitting shells adapted to envelope the instep portion of a shoe and movable laterally toward and away from each other; means for locking said second pair of shells relative to each

other in divers lateral positions; means on said second named shells adapted to engage the walking surface; means on said second named shells adapted to rest upon the welt of a shoe; pivotal connections between said first and second named pairs of shells; means engageable with the shank portion of the sole of a shoe; and resilient means for connecting said engaging means and said first named pair of shells to maintain the latter on a shoe.

17. In a foot protector the combination of a shell connectable to and shaped to envelop the toe section of a shoe; an abutment on said shell adapted to rest upon the welt of a shoe; a second shell, shaped to envelop the instep portion 15 of a shoe; downwardly projecting means on said second shell adapted to engage the walking surface; a pivotal connection between said first and second shells and independent of the shoe; and means for maintaining said shells on a shoe. 20

18. In a foot protector the combination of a shell connectable to and shaped to envelop the toe section of a shoe; an abutment on said shell adapted to rest upon the welt of a shoe; a second shell, shaped to envelop the instep portion 25 of a shoe; a pivotal connection between said first and second shells and independent of the shoe; yoke means insertable under the instep portion of a shoe sole for engagement with opposite sides thereof; and resilient means connecting said yoke 30 means and said first shell for maintaining the latter and said second shell on a shoe.

GEORGE A. MORIARTY.
